US00D454747S

(12) **United States Design Patent** (10) Patent No.: **US D454,747 S**
 Kraska et al. (45) Date of Patent: **** Mar. 26, 2002**

- (54) **DISPOSABLE PLASTIC SHEET ANESTHESIA INFECTION CONTROL BARRIER**
- (76) Inventors: **Joseph J. Kraska**, 11035 - 41 Ave. North, Plymouth, MN (US) 55441; **Frederick B. Keen**, 3028 Dupont Ave. South, Minneapolis, MN (US) 55408; **Warren V. Bigelow**, 5712 Auto Club Cir., Bloomington, MN (US) 55437
- (**) Term: **14 Years**
- (21) Appl. No.: **29/124,737**
- (22) Filed: **Jun. 9, 2000**
- (51) LOC (7) Cl. **06-13**
- (52) U.S. Cl. **D6/602**
- (58) Field of Search D6/595, 596, 597, D6/599, 601, 602, 603, 604, 605, 606, 608; D2/720, 728, 823, 860, 861; D8/403; D24/184, 189, 192; 2/114, 914, 915; 5/417, 418, 419, 420, 484, 486, 495, 499, 630, 631, 632, 633, 636, 637, 638, 639, 640, 641, 644, 645, 646, 648, 650, 651, 652, 652.1, 653, 654, 655, 655.3, 655.4, 655.9, 656, 657, 657.5, 663, 688, 690, 706, 710, 717, 718, 727, 731, 733, 736, 737, 739; 15/208, 209.1, 210.1; 128/849, 853, 854

(57) **CLAIM**

The ornamental design for a disposable plastic sheet anesthesia infection control barrier, as shown and described.

DESCRIPTION

FIG. 1 is a front perspective view of a disposable plastic sheet anesthesia infection control barrier, showing our new design;

FIG. 2 is a front view thereof;

FIG. 3 is a rear view thereof;

FIG. 4 is a right side view thereof;

FIG. 5 is a left side view thereof; and,

FIG. 6 is a top view thereof.

1 Claim, 1 Drawing Sheet
